UNITED STATES PATENT OFFICE

EDWARD J. VON RUDEN, OF CASHTON, WISCONSIN

WATER HEATER

Application filed March 20, 1931. Serial No. 524,181.

This invention relates to water heaters and has for the primary object, the provision of a device which may be easily and quickly installed in the water system of a dwelling or 5 like place and provides means whereby water may be electrically heated in varying quantities according to the wishes of the user.

Another object of this invention is the provision of a heating chamber placed in communication with the water system and having electrical means controlled by a manually actuated switch conveniently located adjacent the faucet of a washstand or the like whereby a person may set the device to heat 15 a desired amount of water prior to dispensing the water by way of the faucet.

A further object of this invention is the provision of a water heater of the above stated character which will be simple, durable and efficient and which may be manufactured and sold at a comparatively low cost.

With these and other objects in view, this 25 invention consists in certain novel features of construction, combination and arrangement of parts to be hereinafter more fully described and claimed.

For a complete understanding of my invention, reference is to be had to the following description and accompanying drawings, in which

Figure 1 is a side elevation partly in section illustrating a water heater applied to a 35 water system and constructed in accordance with my invention.

Figure 2 is a sectional view illustrating the heating chamber with the wiring diagram associated therewith.

Figure 3 is a horizontal sectional view illustrating one of the heating elements located within the heating chamber.

Figure 4 is a fragmentary sectional view illustrating on an enlarged scale the mounting of the heating elements within the heating chamber.

Figure 5 is a front elevation illustrating a control switch.

Figure 6 is a sectional view taken on the 50 line 6-6 of Figure 5.

Figure 7 is a transverse sectional view illustrating a portion of the control switch.

Referring in detail to the drawings, the numeral 1 indicates a heating chamber provided with inlet and outlet pipes 2 and 3 which are 55 connected in a water supply system 4 as clearly shown in Figure 1. The pipe 5 comprising a part of the water system, which is connected to the outlet pipe 3, extends through the wall 6 of a building or like structure and 60 has a faucet 7 disposed over a washbasin 8.

It will be noted that the heating chamber can be easily and quickly installed in the water system by referring to Figure 1 and the heating chamber may be of any desired shape, 65 preferably rectangular as shown in Figures 1 and 2 and is provided with a removable wall 9 secured to the heating chamber by bolts or like fasteners 10 with suitable gaskets to establish a leak-proof connection. A heat 70 insulating lining 11 is located against the inner faces of the walls of the heating chamber to prevent loss of heat and may be of any material suitable for the purpose and secured to the chamber in any well known 75 manner. The heating chamber is divided into a plurality of spaces by heating plates 12 mounted on flanges 13 carried by the walls of the heating chamber and each heating plate has one end spaced from the adjacent wall of 80 the heating chamber to establish a water passage from one space to another as clearly shown in Figure 2. The opposite ends of the heating plates have tubular members 14 85 formed integrally therewith and extend through apertures in the removable wall 9 and are screw-threaded to receive fasteners 15 in the form of nuts adapted to be turned against the outer face of the removable wall. 90

The openings receiving the sleeves 14 are flanged or provided with bosses 16 fitting into correspondingly shaped recesses in the plates 12, thus, it will be seen that the heating plates are firmly supported within the heating 95 chamber and are capable of being removed therefrom by detaching the removable wall 9 and also any one of the heating plates can be easily detached from the removable wall, when desired.

The opposite wall of the heating chamber 1 from the removable wall 9 is apertured to receive the screw-threaded shanks 17 of dividing plates 19 and the stems 17 have nuts 5 threaded thereon. The dividing plates are recessed to receive bosses or flanged portions 18 about the openings receiving the stem 17, thus cooperating with the stems and nuts in firmly securing the dividing plates within the 10 heating chamber. The opposite ends of the dividing plates from the ends carrying the stems 17 are spaced from the removable wall 9 to establish water passages and by reference to Figure 2 it will be seen that due to the 15 arrangement of the heating plates and the dividing plates, the water passing upwardly through the heating chamber is compelled to flow in a zigzag course and also to pass over the entire length of the heating plates thereby 20 effectively heating the water during its passage through the heating chamber.

By reference to Figure 2 it will be seen that the heating and dividing plates 12 and 19 cooperate with each other in dividing the heating chamber into spaces of different sizes for the purpose of containing different quantities of water and which heating plates 12 have an electrical heating filament which is 25 connected to an electrical conductor 21 leading to one pole of an electrical source (not shown). The other end of each filament is connected to an electrical conductor 22. The electrical conductors 21 and 22 are connected to each of the filaments 20 and pass through the tubular members 14, and each conductor 22 is connected to a contact 23 forming part 30 of a control switch 24. The control switch is located in an opening formed in the wall 35 6 above a faucet 7 and comprises a casing 25 provided with a dial face 26 bearing characters designating different quantities of water and are arranged on the dial face according to the sizes or capacities of the spaces for the 40 water within the heating chamber and formed by the heating plates and dividing plates 12 and 19 respectively. A sleeve 27 is journaled in the casing 25 and carries at its outer end a finger piece 28 and an arm 29 at its inner end 45 and on which is formed an arcuate-shaped contact member 30. The contact member 30 is movable over a partition or panel 31 on which are mounted in spaced relation the contacts 23. The sleeve is electrically connected to the 50 electrical source by a conductor 32 which has interposed therein a main control switch 33 in the form of a shaft 34 journaled within the sleeve 27 and insulated therefrom. The outer end of the shaft 34 carries a finger piece 35 55 while the inner end has secured thereto a contact arm 36 movable into and out of engagement with a contact 37 located in a chamber 38 of the casing 25. It is to be understood that the movable contact 36 and the contact 60 37 form a part of the main control switch 33

and when said contacts are disengaged the circuit to the heating plates is broken.

A small electric lamp 39 is mounted in a reflector 40 carried by the casing 25 and located over the dial face 26 and is electrically connected to the conductors 21 and 32 by conductors 41 and which will be illuminated when the switch 33 is in closed position indicating that the device is in operation. 70

An indicator 42 is carried by the sleeve 27 75 and is movable over the characters on the dial face 26 by the operation of the finger piece 28.

In operation, a person desiring to heat a certain quantity of water moves the indicator in alignment with the desired character on the dial face 26 by moving the finger piece 28 which also moves the contact member 30 into engagement with the desired number of contacts 23 and then closes the switch 33 by 80 operating the finger piece 35. The desired number of heating plates 12 according to the quantity of heated water wanted by the person is then in circuit with the electrical source and after waiting a sufficient length 85 of time, the faucet 7 is opened allowing the heated water to flow into the basin 8. If desired a suitable temperature gage may be mounted at any desired point relative to the basin 8 and in communication with the interior of the heating chamber 1 that a person may at a glance determine to what degree the desired quantity of water has been heated. 90

From the foregoing description it will be 100 seen that it is possible for a person to heat water from small quantities to large quantities by simply regulating or moving the indicator into alignment with the desired character on the dial face 26. 105

While I have shown and described the preferred embodiment of my invention, it will be understood that minor changes in construction, combination, and arrangement of parts may be made without departing from the 110 spirit and scope of the invention, as claimed.

Having thus described my invention, what I claim is:

An electrical water heater comprising a 115 heating chamber to receive water from a source and having a controlled outlet, partitions in said chamber to divide the latter into compartments of different sizes, said partitions spaced slightly from one wall of the chamber to provide restricted passages between the compartments, an electrical heating element for each compartment, and each heating element being of a size to contact with the walls of the chamber except one wall of the latter to provide a restricted passage; the restricted passages formed by the heating elements being located at an opposite side of the heating chamber from the passages formed by the partitions, a main switch 120 connected to an electrical source and to one 125 130

5 pole of each of the heating elements, a manually operated switch electrically connected to the main switch and contacts electrically connected to the other poles of the heating elements and adapted to be engaged by the manually operated switch whereby one or more of the heating elements may be connected to the electrical source for heating the water in the differential compartments.

10 In testimony whereof I affix my signature.

EDWARD J. VON RUDEN.
